(57) CLAIM

I claim the ornamental design for the wall hanging, as shown and described.

DESCRIPTION

FIG. 1 is a front view of the wall hanging;

FIG. 2 is top view of the wall hanging;

FIG. 3 is a bottom view of the wall hanging;

FIG. 4 is a right side view of the wall hanging;

FIG. 5 is a left side view of the wall hanging; and,

FIG. 6 is an isometric view of the wall hanging.

The broken lines shown in the drawings represent unclaimed portions of the wall hanging and form no part thereof.
